UNITED STATES PATENT OFFICE

169,999

FLUORESCENT TUBE LIGHTING FIXTURE

George Ainsworth, New Hyde Park, N. Y.

Application October 15, 1952, Serial No. 21,845

Term of patent 14 years

(Cl. D48—23)

To all whom it may concern:

Be it known that I, George Ainsworth, a citizen of the United States, residing at New Hyde Park, county of Nassau, State of New York, have invented a new, original, and ornamental Design for a Fluorescent Tube Lighting Fixture, of which the following is a specification, reference being had to the accompanying drawing, forming part thereof, wherein

The single figure of the drawing is a bottom perspective view of a fluorescent tube lighting fixture showing my new design; one pair of supports being partly broken away for convenience

of illustration. The design is of arbitrary overall length.

I claim:

The ornamental design for a fluorescent tube lighting fixture, as shown and described.

GEORGE AINSWORTH.
